AWNING HOOD

Clyde D. Lowry, Toledo, Ohio, assignor to Libbey-Owens-Ford Glass Company, Toledo, Ohio, a corporation of Ohio

Application August 1, 1938, Serial No. 222,311

11 Claims. (Cl. 156—15)

The present invention relates to improvements in awning hoods for store fronts and the like.

Aawning hoods of extruded aluminum and bronze are becoming quite popular for use on store fronts and the like for protecting the awning, when rolled up, from the weather as well as for increasing the attractiveness of the building front. Heretofore, it has been customary to extrude these hoods in one piece but in order to do this, it is necessary for the hood to be made of relatively heavy gauge which not only materially increases the cost of the hood, due to the relatively large amount of material required, but which also renders the hood objectionable because of its weight. This is especially true of hoods of extruded bronze. It is the purpose of this invention to permit the formation of an awning hood of extruded aluminum or bronze of relatively thinner gauge, whereby to materially reduce the amount of material required as well as reducing the overall weight of the hood along with its cost.

Another object of the invention is the provision of an awning hood of extruded metal made up of a plurality of separate sections associated with one another in a novel manner so that the hood may be made of any desired width.

Another object of the invention is the provision of an awning hood so constructed that different types of adapters may be associated therewith to permit the hood to be used either in connection with a transom or with "Vitrolite" or other structural glass panels or slabs.

Other objects and advantages of the invention will become more apparent during the course of the following description, when taken in connection with the accompanying drawing.

In the drawing, wherein like numerals are employed to designate like parts throughout the same:

Fig. 1 is a front elevation of an awning hood constructed in accordance with the invention;

Fig. 2 is a vertical section taken substantially on line 2—2 of Fig. 1; and

Fig. 3 is a transverse sectional view similar to Fig. 2 but showing the use of another type of awning hood adapter.

With reference to Figs. 1 and 2 of the drawing, 5 refers generally to a portion of the front wall of a building having a window glazed with a sheet or pane of glass 6 supported in the window opening by the metal sash construction 7. Arranged above the window 6 is a transom glazed with a sheet or pane of glass 8 mounted in the transom opening by the metal sash construction 9 which

may be supported upon the transom bar 10. The awning hood provided by the invention is designated in its entirety by the numeral 11, said hood being disposed directly beneath the transom 8 while arranged between the said hood and window 6 are metal filler strips 12.

The awning hood 11 is preferably of extruded aluminum or bronze and is composed of a plurality of sections interlocked with and preferably detachably connected to one another. As shown, the hood comprises an inner longitudinally extending section 13, an intermediate section 14 and an outer section 15; said outer section being of any desired ornamental contour but which is here illustrated as curving forwardly and downwardly to provide a so-called bull-nose effect having ornamental ribs or reeds 16 at its outer end.

The inner section 13 of the hood is provided

20 adjacent its inner end with a rearwardly and downwardly extending back member 17 which may be secured to the supporting wall 5 in any desired manner, such as by screws or the like 18. Formed at the lower end of the back member 17 is a forwardly offset depending web 19 having its lower end received within a channel 20 provided at the upper end of the filler strip 12. The channel 20 is formed between the upstanding flanges 21 and 22, the flange 22 being received behind the web 19 and secured to the supporting wall 5 by screws or the like 23. Formed integral with the front surface of the web 19, adjacent the lower end thereof, is a hook shaped portion 24 which fits over the upper edge of the flange 21 to provide a neat appearing connection between the hood 11 and filler strip 12.

The inner section 13 of the hood is provided at its rear end with an upstanding vertical leg 25 terminating at its upper end in a forwardly directed wedge portion 26 having a horizontal flat upper surface and a beveled lower surface 27. The wedge portion 26 cooperates with the upper surface of the inner section 13 to form a forwardly facing horizontal groove or channel 28. This construction is provided so that there can be associated with the hood 11 a suitable adapter, indicated at 29 in Fig. 2, to permit use of the said hood with the transom 8.

The adapter 29 comprises a horizontal base 50 plate 30 supported upon the transom bar 10 and secured thereto if desired by screws or the like 31. The base plate 30 is provided at its forward end with a depending leg 32 terminating in a rearwardly extending wedge portion 33 which is snugly received within the groove or channel

28 of the hood. The bottom surface of the wedge portion 33 is flat and engages the upper surface of the hood section 13, while the upper surface thereof is beveled as at 34 to correspond to the beveled surface 27 of wedge portion 26. The adapter 29 is also shown as provided at its rear end with a similar but forwardly directed wedge portion 35 spaced above the base plate 30 and adapted to be received within a groove or channel 36 provided at the rear of the metal sash construction 9 of the transom 8.

The inner section 13 of the hood is provided adjacent its outer end with a downwardly and forwardly curved supporting flange 37 and at its extreme end with a down-turned lip 38, said flange and lip cooperating to form a substantially vertical groove 39. The intermediate section 14 of the hood is supported upon the flange 37 and is provided at its inner end with an upwardly curved portion or tongue 40 which is received within the groove 39.

When assembling the intermediate section 14 of the hood with the inner section 13, the curved inner end portion or tongue 40 of the intermediate section is inserted within the groove 39 of the inner section by tilting the said intermediate section upwardly as indicated in broken lines in Fig. 2 so that the curved inner end thereof can be slipped into the groove 39, and as the said curved inner end is moved into the groove, the said section is simultaneously lowered until it rests upon the flange 37. The two sections can then be secured to one another, if desired, by bolts or the like 41, it being preferred that said sections be detachably connected together.

The intermediate section 14 is formed at its outer end in the same manner as the outer end of inner section 13, while the inner end of outer section 15 is formed in the same way as the inner end of intermediate section 14 so that the outer section 15 may be associated with the intermediate section 14 in the same manner that intermediate section 14 is associated with inner section 13 as indicated generally at 42. It will, of course, be appreciated that with this arrangement any desired number of intermediate sections 14 may be used depending upon the width of hood desired. The hood 11 may be used as a covering for any conventional or preferred type of roller awning which is located beneath the hood adjacent the back member 17 as diagrammatically indicated at A.

In Fig. 3 is illustrated another type of adapter which may be associated with the hood to permit its use with slabs or panels of "Vitrolite" or other structural glass located directly above the transom bar 10. The adapter is here designated in its entirety by the numeral 43 and is provided with a rearwardly directed wedge portion 44 adapted to be received within the groove or channel 28 at the rear end of the hood. Formed at the outer end of the wedge portion 44 is an upstanding vertical leg 45 having formed integral therewith a rearwardly extending horizontal ledge 46 which terminates at its inner end in a vertical attaching flange 47 secured to the supporting wall 5 by screws or the like 48. The slabs or panels 49 of "Vitrolite" or other structural glass are supported at their bottom edges upon the horizontal ledge 46 of the adapter and secured to the supporting wall 5 by mortar or cement 50. The vertical leg 45 of the adapter preferably terminates at its upper edge in a bead 51 which overlaps the lower marginal portions of the slabs or panels 49 to give a neat appearance.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. An awning hood of the character described, comprising a plurality of longitudinally extending sections arranged side by side, one of said sections being provided with a groove and a substantially horizontal supporting portion extending forwardly from said groove while a second section is supported upon said supporting portion and has a tongue received within said groove.
2. An awning hood of the character described, comprising a plurality of longitudinally extending sections arranged side by side, one of said sections being provided with a groove and a substantially horizontal supporting portion extending forwardly from said groove while a second section has a portion overlapping said supporting portion and a tongue received within said groove, and means for detachably connecting said overlapping portions together.
3. An awning hood of the character described, including a substantially horizontal top member formed at its rear end with a vertical leg and a forwardly directed wedge portion providing a horizontally disposed channel for receiving means adapting said hood to different arrangements, said wedge portion having a flat upper surface and a beveled lower surface.
4. An awning hood of the character described, comprising a plurality of longitudinally extending sections arranged side by side, and means for connecting said sections together, the inner section being provided at its rear end with a vertical leg and a forwardly directed wedge portion providing a horizontally disposed channel for receiving means adapting said hood to different arrangements, said wedge portion having a flat upper surface and a beveled lower surface.
5. An awning hood of the character described, comprising a plurality of longitudinally extending sections arranged side by side and having portions overlapping and interengaging one another, and means for rigidly securing said overlapping portions together, the inner section being provided at its rear end with a vertical leg and a forwardly directed wedge portion providing a horizontally disposed channel for receiving means adapting said hood to different arrangements, said wedge portion having a flat upper surface and a beveled lower surface.
6. An awning hood of the character described, comprising a plurality of longitudinally extending sections arranged side by side and having overlapping portions and complementary tongue and groove connections interlocking one another, and means passing through said overlapping portions for rigidly securing said sections together, the inner section being provided at its rear end with a vertical leg and a forwardly directed wedge portion providing a horizontally disposed channel for receiving means adapting said hood to different arrangements, said wedge portion having a flat upper surface and a beveled lower surface.
7. An awning hood of the character described, comprising a plurality of longitudinally extending sections arranged side by side and having portions overlapping one another, and means for de-

tachably connecting said overlapping portions together, the inner section being provided at its rear end with a vertical leg and a forwardly directed wedge portion providing a horizontally disposed channel for receiving means adapting said hood to different arrangements, said wedge portion having a flat upper surface and a beveled lower surface.

8. An awning hood of the character described, comprising a plurality of longitudinally extending sections arranged side by side, one of said sections being provided with a groove and a substantially horizontal supporting portion extending forwardly from said groove while a second section is supported upon said supporting portion and has a tongue received within said groove, the inner section being provided at its rear end with a vertical leg and a forwardly directed portion providing a horizontally disposed channel for receiving means adapting said hood to different arrangements.

9. An awning hood of the character described, comprising a plurality of longitudinally extending sections arranged side by side, one of said sections being provided with a groove and a substantially horizontal supporting portion extending forwardly from said groove while a second section has a portion overlapping said supporting portion and a tongue received within said groove, and means for detachably connecting said overlapping portions together, the inner section being provided at its rear end with a vertical leg and a forwardly directed portion providing a horizontally

disposed channel for receiving means adapting said hood to different arrangements.

10. The combination with an awning hood comprising a substantially horizontal top member formed at its rear end with a vertical leg and a forwardly directed wedge portion providing a horizontally disposed channel, of an adapter associated with said awning hood for adapting it to different arrangements comprising a substantially horizontal base plate provided at its forward end with a depending leg terminating in a rearwardly directed wedge portion which is snugly received within the horizontally disposed channel in said awning hood.

11. The combination with an awning hood comprising a substantially horizontal top member formed at its rear end with a vertical leg and a forwardly directed wedge portion providing a horizontally disposed channel, said wedge portion having a flat upper surface and a beveled lower surface, of an adapter associated with said awning hood for adapting it to different arrangements comprising a substantially horizontal base plate provided at its forward end with a depending leg terminating in a rearwardly directed wedge portion which is snugly received within the horizontally disposed channel in said awning hood, the bottom surface of the wedge portion of said adapter being flat and engaging the upper surface of the awning hood while the upper surface of the last said wedge portion is beveled to correspond to the beveled surface of the wedge portion of said awning hood.

CLYDE D. LOWRY.
